UNITED STATES PATENT OFFICE.

HARRY A. DOUGLAS, OF BRONSON, MICHIGAN.

CASING HAVING LIGHT-TRANSMITTING CLOSURE.

Application filed July 2, 1927. Serial No. 203,224.

My invention relates to casings which are provided with light transmitting closures for the purpose of transmitting light from the interior of the casing to the exterior of the casing or from the exterior of the casing to the interior thereof, and comprises a body part, a light transmitting closure, a frame for the closure, and a closure retaining member positioned to hold the closure in assembly with the frame, the retaining member and body part having engaging portions that hold the closure frame in assembly with the casing body.

In the preferred embodiment of the invention the retaining member is in the form of a ring of spring metal which is bent to hold the closure and its frame in assembly by spring pressure, the ring desirably engaging the closure at spaced apart places and having a part engaging the frame between these places, the ring being spaced from the closure between its places of engagement with the closure in order that it may exert spring pressure upon the frame, and, consequently, spring pressure upon the closure. The retaining ring is provided with a portion between its places of engagement with the closure that engages a portion upon the body part of the casing in a manner to press this body part and the closure frame together whereby the assembly of the three casing parts, the body part, the frame and the closure, is completed. The body part of the casing is desirably formed with bayonet projections and the portions of the retaining member that are engaged with the casing body are formed with bayonet slots or channels that receive said projections.

The invention will be more fully explained in connection with the accompanying drawing in which Fig. 1 is a longitudinal section of a casing which is shaped to hold an incandescent lamp whose light passes through the closure of the casing; Fig. 2 is a sectional view on line 2-2 of Fig. 1; Fig. 3 is a sectional view on line 3-3 of Fig. 1, on a larger scale; Fig. 4 illustrates the body part of the casing in perspective and in separate relation from the closure frame and retaining ring, which are shown in section, and the closure which is shown in elevation and in assembly with the frame; and Fig. 5 is a perspective view of the retaining ring.

The body part 1 of the casing is shown of concave form. It may be made of metal

and have its interior surface bright to constitute a reflector. The casing illustrated is shown as being adapted to contain an incandescent lamp 2 so that light will shine from the interior of the casing to the exterior thereof though the direction in which the light passes either into or out of the casing is immaterial in so far as the invention is concerned. The incandescent lamp 2 is detachably secured to a socket 3 which is equipped with circuit terminals for including the lamp in circuit. The remaining parts of the casing are the light transmitting closure 4, preferably of glass, and an annular frame 5 for this closure, said casing body 1 being at the rear side of said closure 4. This frame is formed with an internal shoulder 6 which is at the rear side of the closure 4 and is seated upon an external shoulder 7 formed upon the casing part 1 near the front thereof. The frame 5 has a forward internal shoulder 8 which rests upon the flange 9 of the light transmitting closure 4. By means of my invention, the shoulders 6 and 7 are spring pressed into engagement as are also the shoulder 8 and the front side of the closure at its flange 9. To this end I employ a retaining member that is preferably in the form of a resilient ring of spring sheet metal which is bent at diametrically opposite places to have two portions 10 and 11 which are engaged with one of the casing parts 4, 5, preferably the part 4, the ring being spaced apart from the casing part 4 between the engaging portions 10 and 11 whereby the portions of the ring, where thus spaced apart from the casing part 4, are free to be flexed perpendicularly to the general plane of the closure 4 so that it may exert the desired spring pressure to maintain the three casing parts 1, 4 and 5 in assembly. The ring is provided with two rearwardly extending fingers 12 that are located between the ring portions 10 and 11 and which are located at and upon the parts of the ring which are spaced apart from the closure 4 and are flexible perpendicularly to the general plane of the closure. These fingers project against the inner and channeled side of the shoulder 6 and serve slightly to depress the portions of the ring contiguous thereto toward the closure 4, these ring portions thus exerting spring pressure upon the shoulder 6 through the intermediation of said fingers, whereby the closure 4 is yieldingly maintained in engagement with the

frame 5 but with sufficient spring pressure normally to prevent separation of said closure and frame. The ring is also equipped with catches that are in the form of fingers 5 13 that are formed with bayonet slots or channels 14, these fingers also being located between the ring portions 10 and 11 and extending from parts of the ring that are spaced apart from the closure 4. The casing body 1 is equipped with bayonet projections 15 which are inwardly continued from the front rim of the casing body and which are received in the bayonet slots 14 when the frame 5 is seated upon the shoulder 7 and 10 is suitably turned. The bayonet slots 14 and projections 15 are so disposed that when they are engaged, the ring will be placed under tension by reason of such engagement whereby the casing parts 1 and 5 will be 15 pressed each toward the other to hold them firmly in engagement. One of the fingers 13 is disposed between the stop lug 16 and one of the bayonet projections 15, this stop lug limiting the extent to which the frame 20 5 may be turned in one direction, being positioned in the path of said finger 13.

While I have shown the casing body 1 as being deep enough to hold an incandescent lamp and have illustrated the closure 4 as 25 being convex, it is to be understood that the invention is not to be thus limited nor is it

to be limited to other precise details of construction illustrated and specifically described.

Changes may be made without departing 35 from the invention.

Having thus described my invention, I claim:

A casing including a casing body; a light transmitting closure at the rear of which 40 said body is disposed; an annular frame surrounding the closure and having an internal shoulder at the front side of the closure and an additional internal shoulder which is at 45 and spaced apart from the rear side of said closure; a resilient retaining ring having portions flexible perpendicularly to the general plane of said closure and interposed between said closure and the aforesaid additional internal shoulder of the annular 50 frame, said ring having rearwardly extending fingers upon its aforesaid flexible portions and pressing upon this shoulder to press the first aforesaid internal shoulder upon the front side of the closure; and 55 catches carried by said retaining ring and engaging the aforesaid casing body and holding it against said annular frame.

In witness whereof, I hereunto subscribe my name.

HARRY A. DOUGLAS.
